CONTINUOUS PULPER AND SELECTOR

Harold Donald Wells, Glens Falls, N. Y.

Application September 20, 1943, Serial No. 503,120

2 Claims. (Cl. 92—23)

1

The invention relates to machines for converting various kinds of paper-making materials into pulp and continuously discharging the pulp through a selector screen, the principal object being to provide a new and improved pulp-screening means which will pulsate the pulp as it is being screened and will, therefore, prevent screen clogging.

Another object is to provide the aforesaid screening means in the form of an attachment readily applicable to a pulping tank.

Yet another aim is to so relate the screening means with a rotary pulp beater and circulator, that the latter will circulate the pulp across the screen and the pulp will be pulsated as it flows across said screen, insuring efficient screening without danger of screen clogging.

A still further object is the provision of a relatively simple and inexpensive construction which will be highly efficient, reliable and long-lived.

With the foregoing in view, the invention resides in the novel subject matter hereinafter described and claimed, description being accomplished by reference to the accompanying drawings.

Figure 1 is a central vertical sectional view through a pulper and selector constructed in accordance with the invention.

Figure 2 is a horizontal sectional view on line 2—2 of Fig. 1.

Figure 3 is an enlarged vertical sectional view through the screening means, on line 3—3 of Fig. 1.

Figure 4 is a transverse sectional view on line 4—4 of Fig. 3.

Figure 5 is a reduced side elevation showing the screening means mounted on the vertical side wall of the tank instead of upon the tank bottom as in the preceding views.

A preferred construction has been illustrated and will be rather specifically described, with the understanding, however, that within the scope of the invention as claimed, variations may be made.

A pulping tank 6 is shown mounted in an opening in a floor 7, upon an appropriate framework 8, said tank 6 having a cylindrical side wall 9, a flat bottom 10, and a peripheral bottom portion 10' curving upwardly from said flat bottom to said side wall. Mounted on a vertical axis directly over the central portion of the tank bottom 10, is a substantially conical, spirally-bladed beater and impeller comprising a pulp beating and circulating disk 11 having vanes 12 to act upon the pulp and circulate the latter outwardly,

2

upwardly, inwardly and downwardly, (in other words, vertically) as indicated by the arrows in Fig. 1. The disk 11 is close to the bottom 10 and is mounted on a shaft 13 driven by an electric motor 14 and an appropriate belt drive 15, said shaft being mounted in an appropriate bearing structure 16.

Between the disk 11 and the curved bottom portion 10', the bottom 10 is formed with a rectangular pulp discharge opening 17 for which a screen 18 is provided. A continuous diaphragm 19 is appropriately secured at 20 to the marginal portion of the screen 18 and projects outwardly from all edges of said screen, said diaphragm being fluid-tightly clamped against the lower side of the bottom 10, by means of a continuous laterally projecting attaching flange 21 on a pulp receiving and discharging casing 22 which is disposed under the tank 6. This casing is provided with a continuous side wall 23, the upper edge of which carries the flange 21, the top of the casing being open. This casing is also provided with a bottom 24 secured to the lower edge of the continuous side wall 23. Cap screws or the like 25 secure the flange 21 to the bottom 10 and fluid-tight clamping of the casing 22 to the tank 6 is thus effected, the diaphragm 19 acting as a gasket and also establishing a yieldable connection between the screen 18 and the tank so that said screen may be vertically vibrated to pulsate the pulp circulating over it, thus facilitating screening and insuring against clogging. The selected pulp which passes through the screen 18 is received in the casing 22 and discharged through an appropriate outlet line 26.

Secured to the central longitudinal portion of the screen 18, near the ends of this screen, are two cylindrical, downwardly projecting bosses 27, said bosses preferably having flanges 28 welded or otherwise secured to the lower side of said screen. Directly opposite and aligned with these bosses, there are two upwardly projecting bushings 29 which are welded or otherwise secured to the casing bottom 24. Elastic sleeves 30 of rubber or the like extend from the bosses 27 to the bushings 29 and are secured around said bosses and bushings by hose clamps or the like 31. Within the sleeves 30 are two rods 32 whose upper ends are suitably secured at 33 to the bosses 27. The lower portions of these rods 32 pass slidably through the bushings 29 and are secured to yokes 34 which are vertically reciprocable by means of eccentrics 35 on a shaft 36 which is mounted in appropriate bearings 37 projecting downwardly from the casing bottom 24. As is customary

with eccentrics, each eccentric 35 is rotatable within a block 38 which is horizontally reciprocable in the yoke 34.

For driving the shaft 36, a small electric motor 39 is mounted directly on the casing bottom 24 and is connected with said shaft by an appropriate belt drive 40.

It will be seen from the above that the screening means constitutes a compact unit carrying its own screen-vibrating means, and that said unit is readily attachable to a pulping tank. While in most views, this unit is shown secured to the tank bottom 10, Fig. 5 illustrates it mounted on the vertical wall 9 of the tank, upon a suitable outwardly bulged portion 41 of said wall. It is also of course possible that the beating and circulating disk 11 could be mounted at the inner side of the tank side wall 9 instead of directly over the bottom 10.

Bundles or bales of paper-making materials, or loose batches of such materials, may be discharged into the tank 8 and with the two motors 14 and 39 operating, defibering, beating, brushing, scrubbing, color mixing, size and alum mixing, etc., may be continuously and rapidly performed. The eccentrics 35 of course rapidly reciprocate the rods 32 and as their strokes are very short, the motion imparted to the screen 8 may be considered as vibratory, with the result that the pulp being circulated across said screen, is rapidly pulsated which not only facilitates pulp selection but prevents screen clogging. As the rods 32 reciprocate, the elastic sleeves 30 of course yield, and these sleeves in their association with the bosses 27 and bushings 29, seal the casing 22 against any escape of liquid around the rods.

From the foregoing, taken in connection with the accompanying drawings, it will be seen that novel and advantageous provision has been made for carrying out the objects of the invention, and while preferred features have been disclosed, attention is again invited to the possibility of making variations within the scope of the invention as claimed.

I claim:

1. A pulper and selector comprising a pulping tank, a spirally-bladed beater and impeller mounted in said tank for beating the tank-con-

tained stock and vertically circulating it, one of the walls of said tank having a vibratably mounted selector screen across which high-velocity stock is swept by said spirally-bladed beater and impeller, and means at the outer side of said selector screen for vibrately actuating said screen while the stock is being vertically circulated and swept across said screen by said spirally bladed beater and impeller.

2. A pulper and selector comprising a pulping tank having a cylindrical side wall and a bottom peripherally inclined to said side wall, a substantially conical impeller and beater body mounted on a vertical axis directly over and in close relation with the central portion of said bottom, said conical body having spirally directed blades on its upper side and extending substantially from its center to its periphery for beating and vertically circulating the tank-contained stock, said bottom having a vibratably mounted selector screen across which high-velocity stock is swept by said spirally directed blades, said screen extending substantially from said body to the inclined peripheral portion of said bottom and being substantially flush with the upper side of said bottom, and means at the outer side of said selector screen for vibrately actuating said screen while the stock is being vertically circulated and swept across it by said spirally directed blades of said body.

HAROLD DONALD WELLS.
